Attorney

UNITED STATES PATENT OFFICE.

EARL NIXON, OF BOLIVAR, PENNSYLVANIA.

POWER-OPERATED SAWING MECHANISM.

Application filed September 15, 1922. Serial No. 588,426.

To all whom it may concern:

Be it known that I, EARL NIXON, a citizen of the United States, residing at Bolivar, in the county of Westmoreland and 5 State of Pennsylvania, have invented certain new and useful Improvements in Power-Operated Sawing Mechanisms, of which the following is a specification.

This invention relates to an improved 10 power operated sawing mechanism.

The primary object of this invention is the provision of a relatively simple type of power operated saw, which embodies novel features of mounting the same to permit of 15 facile operation.

An important object of this invention is the provision of a power operated saw, embodying a compactly arranged driving mechanism, and a novel type of saw frame 20 permitting of the use of a full length saw blade to effect sawing of meat and other articles.

Other objects and advantages of this invention will be apparent during the course 25 of the following detailed description.

In the accompanying drawings, forming a part of this specification, and wherein similar reference characters designate corresponding parts throughout the several 30 views,

Figure 1 is a side elevation of the improved power operated sawing mechanism, showing the saw arrangement thereof in full and dotted lines to designate various 35 positions thereof.

Figure 2 is a longitudinal cross sectional view, taken substantially on the line 2—2 of Figure 3.

Figure 3 is a side elevation partly in section, showing cooperating features of the 40 improved power operated saw.

Figure 4 is a transverse cross sectional view, taken substantially on the line 4—4 of Figure 3.

Figure 5 is a rear elevation of the mounting of the improved power operated saw.

Figure 6 is a fragmentary view, partly in section, showing the manner in which the improved power operated saw may be movably supported.

In the drawings, wherein for the purpose of illustration is shown but the preferred embodiment of this invention, the letter A generally indicates the improved sawing

mechanism, which principally comprises a 55 work table B; power operated saw C; supporting frame D; and counter balance mechanism E.

The work table B may be of any approved type, including the ordinary chopping block 10, supported as by legs 11.

The improved power operated saw C may include a casing 13, preferably cast of aluminum or similar light material, including the box portion 14 which provides a chamber 15 therein, and a cover 16 which is detachably positioned over one side of the box portion 14, as by the detachable counter

sunk screw elements 17. The box portion 14 may have the rear handle 18 thereon of 70 any formation. A frame 20 is preferably slidably carried by the casing 13, which includes upper and lower portions 21 and 22 respectively, having certain straight line portions thereof which slidably extend into 75 the chamber 15 of the casing 13 through apertures 23 provided in the front wall 24 of the casing 13. The lowermost portion 22 of the frame 20 is of novel formation at

its outer end, being substantially U-shaped 80 in formation, to provide the lowermost substantially horizontal offset portion 26, which extends substantially parallel with the main portion 27 thereof, and in spaced 85 connected relation therewith, as by a bight portion 28. The ends of the portions 21 and 22 extending into the chamber of the casing 13 are guided as by lugs 30 rigid with said

casing 13, and providing passageways 31 for said frame 20. A cross bar 33 preferably 90 connects the portions 21 and 22 of the frame 20 within the chamber 15. The forward end 34 of the frame portion 21 is downturned and provides a pin or other device 35 for the securing of an end of a 95 saw blade 36 thereto; the opposite end of said saw blade 36 being connected as by an adjustable device 37 to the depending end of the frame portion 26, and substantially as is illustrated in Figures 1 and 3 of the 100 drawings. The provision of the novel type of frame portion 22 permits the use of a relatively long blade 36, since when the frame 20 is in its most retracted position

with respect to the casing 13, as is illustrated in Figure 1 of the drawings, the frame portion 26 lies immediately below the lower wall 39 of the casing 13, and in over-

lapping relation therewith, whereby the blade 36 is also in overlapping relation with said casing 13.

The saw reciprocating means 40 is provided as a part of the improved power operated saw C, which includes a worm wheel or gear 41 rotatably mounted as by a pin 42 within the chamber 15 of the casing 13, at the most rearward end thereof adjacent the handle 18. A worm shaft 44 is preferably rotatably mounted within the chamber 15, having opposite ends thereof carried by the top and bottom walls 45 and 39 respectively of the casing 13, so that said worm shaft is in meshing relation with the teeth of the gear wheel 41. In order to effect proper mounting of the worm 44, certain bearing lugs 46 have been provided extended inwardly of the chamber 15 and preferably integral 20 with the casing 13. The top end of the worm shaft 34 extends outwardly of the top wall 45 of the casing 13 and is connected as by a universal joint 48 with a flexible drive shaft 49 of any approved type. A connecting rod 50 is eccentrically pivoted, as at 51, to the worm gear 41, and at its other end is oscillatively connected, as at 52, to the cross bar 33 midway of the ends of the latter.

Referring to the supporting arrangement 30 D, the same includes a substantially L-shaped frame member 52, which includes a leg 52, of straight line formation, which is provided upon its rearward offset end 54 with a plate 55 adapted for detachable connection to a suitable lug 56 provided as a part of the casing 13. The other leg portion 57 of the frame member 52 depends forwardly of the saw C, and has a ring shaped socket end 58 adapted for lateral sliding upon the horizontally positioned guide rod 59 which is supported upon a side 60 of the chopping block 10 in spaced relation therewith, as by supporting brackets 61. A diagonal cross brace 65 may be provided for bracing the leg portions 53 and 57 of the frame member 40 52 to maintain them in stable relation.

Referring to the counter balance mechanism E, the same preferably includes a tubular guide barrel 66 which is vertically mounted, as by a bracket 67; the latter being connected in rigid manner upon the front surface 60 of the chopping block 10, so that the barrel 66 extends upwardly from the chopping surface 68 of block 10. The upper end of the tubular member 66 is preferably provided with a roller or pulley 69 adapted to receive a flexible cable 70 which is trained thereover. One end of the cable 70 may have a counter weight 71 thereon which is adapted for reciprocable disposition in the longitudinal passageway 72 of the tubular guide 66. The opposite end of the cable 70 is preferably attached, as by a clamping clip 73, to the guide member 52 adjacent its offset connecting end 54.

In operation, the flexible cable 49 is connected at its ends remote from the saw C to a suitable power source (not shown) as the shaft of a motor.

Upon operation of the shaft 49, the worm 44 will be rotated, so that the wheel 41 will be moved in order to reciprocate the saw frame 20 through the connecting rod 50, so that the blade 36 may travel back and forth in the ordinary manner for cutting purposes. The operator, of course, grasps the handle 18 and it is merely necessary to lower the saw C onto the article to be cut, which is ordinarily mounted upon the block 10. This lowering operation is manually effected, since the counterweight 71 is adapted to facilitate upward swinging of the free end of the saw into the position substantially illustrated by the dotted lines in Figure 1 of the drawings. The saw C may be laterally adjusted over the chopping block 10 by reason of the lateral sliding connection of the frame 52 with the guide supporting bar 59, the cable 70 permitting of this sliding due to its flexibility.

From the foregoing description of this invention, it can be seen that a relatively simple, yet compact and practical power operated saw mechanism has been provided, which utilizes novel methods of mounting and arrangement of parts so that a full length saw blade may be utilized which will not interfere with the reciprocating mechanism thereof.

Various changes in the shape, size and arrangement of parts, may be made to the form of the invention herein shown and described, without departing from the spirit of this invention or the scope of the claims.

I claim:

1. A device of the class described comprising a supporting arrangement having a handle thereon, a saw blade, a frame having upper and lower strips slidably extending through said supporting arrangement, the upper strip being provided with a down-turned forward portion and adapted for connection with a saw blade, the lower strip having its forward end portion carried downwardly and then rearwardly and having its free end portion extending downwardly and adapted for connection with a saw blade, whereby a relatively long blade may be used which is adapted for exterior overlapping relation with respect to said supporting arrangement when in rearward position with respect thereto, and means carried by said supporting arrangement for reciprocation of said saw.

2. In a saw device, a casing having one end provided with upper and lower openings, a blade carrying frame having upper and lower strips slidably passing through the openings in said casing, the upper strip having its outer end portion provided with a de-

pending arm adapted for connection with a saw blade and the lower strip having its outer end portion extended downwardly and then rearwardly in a plane for extending beneath the casing when moved rearwardly and terminating in means for connection with a saw blade whereby an elongated blade may be secured to the ends of said strips and

move beneath the casing when moved rearwardly, a cross bar connecting said strips 10 within the casing and operating means in the casing connected with the cross bar for imparting reciprocating movement to the frame.

EARL NIXON.
